UNITED STATES PATENT OFFICE.

HENRY SÉCHAUD, OF GENTILLY, FRANCE; MARIE HENRIETTE JEANNE GOURLET-SÉCHAUD EXECUTRIX OF SAID HENRY SÉCHAUD, DECEASED.

MOTOR-VEHICLE.

SPECIFICATION forming part of Letters Patent No. 788,852, dated May 2, 1905.

Application filed December 22, 1902. Serial No. 136,203.

To all whom it may concern:

Be it known that I, HENRY SÉCHAUD, a citizen of the French Republic, residing at Gentilly, Seine, France, have invented certain new and useful Improvements in and Relating to Motor-Vehicles, of which the following is a specification.

This invention has for its object a device which permits of effecting by means of a single appliance changes of direction and velocity, throwing into and out of gear the braking, and also the regulation of motor-vehicles. The combination constituted by this device renders unnecessary all the individual parts hitherto employed for operating the different mechanism, leaves the hands of the driver at liberty, and renders it possible for complete novices to drive motor-vehicles.

The invention is illustrated in the accompanying drawings, in which—

Figure 1 is a general view of a motor-vehicle provided with the device which forms the subject of this invention. Fig. 2 is a corresponding plan view, but with the motor-cover removed. Fig. 3 is a vertical section on the axis of the device. Fig. 4 is a side elevation, upon a smaller scale, corresponding to Fig. 3 and also a section through this figure on the line A B C D. Fig. 5 is an elevation, upon a larger scale, of the steering-pinion and rack. Fig. 6 is a plan view of the upper hand-wheel *f* of Fig. 3. Fig. 7 is an elevation of the sector *r*, Fig. 3; and Fig. 8, a plan view of the same.

The device consists, Figs. 3 and 4, of a ground outer tube *a*, which is brazed at its lower portion to a cage or casing *c* and is carried by a pivot *b*. A tube *d*, arranged within the first, in which it rotates with easy friction, is rigidly connected at its lower portion with a pinion *e* and at its upper portion with a half hand-wheel *f*, carrying a disk *g*, provided with an aperture to permit of the passage of a tube *h*, provided at its lower extremity with a bearing-surface *i* for the spiral spring *j*, the upper extremity of which bears against the disk *g*. The tube *h* is fixed to a disk *k*, provided with pins *l*, which pass through apertures formed in the half hand-

wheel *f* and of which the lower extremities enter cavities formed in a sleeve *m* exterior to the tube *a* and rigid with the lower half *n* of the hand-wheel. One of the arms of the hand-wheel member *f* is provided with an opening *o*, Figs. 3 and 6, serving for the passage of a small bent lever *p*, articulated upon this arm and furnished with a spring. This lever passes through a corresponding opening formed in the lower half *n* of the hand-wheel. The sleeve *m* may engage with the teeth of the notched sector *r*, Figs. 3, 7, 8, mounted upon suitable rods *s*, Fig. 4, rising from the floor *t* of the vehicle and supporting the pivot *b*. This sector is in two parts, arranged endwise in the same horizontal plane, between which parts the tube *a* is able to move. It carries upon its upper edges notches formed upon a circumference described by elements of a circle corresponding to the lower circular section of the sleeve *m*.

The cage *c* supports a gear-wheel *u*, mounted upon a shaft *v*, connected by a universal joint *w* to a grooved shaft *x*, provided with a toothed wheel *y*, engaging with a circular rack *z* of the steering-gear, Figs. 2, 4, and 5. A screw-threaded rod *1*, Figs. 3 and 4, carrying a hand-wheel *2*, passes with slight friction through the disk *k* and engages in an elongated nut *3*, formed at the extremity of a rod *4*, terminating in a fork *5*, articulated in a slotted arm *6*, mounted at the extremity of a shaft *7*, connected by a universal joint *8* to a square shaft *9*, arranged within a universal joint *10*, in which it is adapted to slide, but which it carries with it in its movement of rotation in a similar manner to the device of the shaft *x*. This shaft *9* is connected by a rod *10^a*, Fig. 1, to the regulating parts *10^b*. The cage *c* terminates in a fork *11*, which connects the tube *a* by the intermediary of a rod *12* to the lever *13* of the speed-changing mechanism inclosed in the cage *26^a*, Fig. 1, and the lever *46* of the brake *45*.

The sector *r*, Figs. 7 and 8, comprises a certain number of notches—ten, for example—which when the motor is in the explosion phase correspond to the first notch *I* to the position brake applied and motor thrown out

of gear—that is to say, running free; the second II to brake released, the motor remaining out of gear; the third III, the fourth IV, fifth V, sixth VI to engagement with the low speed with a complete or progressive variation of advance for the ignition. The seventh VII, eighth VIII, ninth IX, and tenth X correspond to engagement with the high speed with variation for the advance of the ignition.

In explaining the operation we may assume the vehicle to be at a standstill and ready to start. The tube *a* occupies its rearmost position, its sleeve *m* being engaged in the notch I of the sector *r*, Fig. 1, this notch corresponding to brake applied and motor out of gear. In order to start the vehicle, the brake is released. To effect this, the two hand-wheels *f* *n* are grasped by the hand and tightened in endeavoring to cause them to approach each other. The half hand-wheel *n* is raised. At the same time it releases the sleeve *m* from the notch I. The hand-wheel and the tube *a* are pressed in the direction indicated by the arrow A, Fig. 1, until the sleeve *m* is opposite the notch II. At this moment the hand-wheel *n* is abandoned and the sleeve *m* is drawn into the notch D D by the spring *j*, which acts by the intermediary of the pins *l*. The tube *a* has oscillated around the pivots *b*, and its lower fork 11 has exerted a thrust upon the rod 12, which, actuating the lever 46, has effected the release of the brake 45. By means of a similar operation the sleeve *m* and the tube *a* are pressed upon the notch III, which corresponds to the low speed. The oscillation of the tube *a* presses the rod 12 in the direction of the arrow 12^a. The lever 13 rocks around its pivot 14 and actuates the transmission-gear 26^a. If it is desired to steer at the same time, it is only necessary to rotate the hand-wheel *f* *n* in one direction or the other. This rotation causes that of the tube *b*, which, by the intermediary of the toothed wheels *e* and *u*, will act upon the shaft *w*, upon the toothed wheel *y*, and the circular rack *z*, connected to the broken steering-levers, Fig. 2. If it is desired to act upon the regulating mechanism, the hand-wheel 2 is rotated in the proper direction, thus causing the slotted arm 6 to rise or descend. This arm actuates the shaft 9, which itself controls, by means of the rod 10, the regulating part 10^a. In the example cited the shaft 9 permits of acting upon the mechanism for regulating the advance of the ignition or the admission of the spirit, when the motor medium is a hydrocarbon, it is equally well adapted, if the motor is operated by steam, to open or close the admission-valve. If the motor is electric, it permits of establishing or interrupting the current. When it is desired to apply the brake, the sleeve *m* is brought into the notch V by acting upon the tube in the reverse direction to that indicated by the arrow A. Traction is thus exerted on the rod 12 and the lever 46,

and the brake is applied. There is thus obtained, by means of a continuous forward movement of the tube *a*, starting and progressive acceleration of velocity, and by the reverse movement the velocity is progressively diminished and disengagement and stoppage are effected. This arrangement is especially applicable to motor-vehicles, but is also adapted to stationary and other engines in which it is desired to produce simultaneously changes of speed, of steering, and of direction of rotation.

The spring *j* may be replaced by an elastic member interposed between the two hand-wheels *f* and *n*. The bent bolt or lever *p* serves to maintain the hand-wheel *n* raised when in certain cases it is not desired to engage the sleeve *m* in the notches of the sector *r*.

Having now particularly described and ascertained the nature of my said invention and in what manner the same is to be performed, what I claim is—

1. The combination with a support, of a tube mounted to swing, means for transmitting the swinging movement thereof, a tube arranged to turn in the swinging tube, means for transmitting the turning movement of said tube, a rod extended through the tube and movable longitudinally, and means for transmitting said longitudinal movement of the rod.

2. The combination with a support, of a tube mounted to swing, means for transmitting the swinging movement thereof, a tube adapted to turn in the swinging tube, means for transmitting the turning movement of said tube, a rod extended through the tube and movable longitudinally, means for transmitting the longitudinal movement of the rod, and a member movably mounted on the first-named tube and working with a relatively stationary part of the support, to hold said first-named tube in the desired position.

3. The combination of a movable member, a rack, a part mounted on the movable member and coacting with the rack to prevent the movement of said member, said part being capable of turning during its engagement with the rack, and a second member carried by the first-named member and arranged to turn independently thereof and having connection with the said part coacting with the rack.

4. The combination of a tube, means for mounting the same to swing on a transverse axis, a rack, a sleeve arranged to turn on the tube and also to move longitudinally thereof into and out of engagement with the rack, a hand-wheel connected with the sleeve, a tube mounted to turn in the first-named tube, a second hand-wheel connected with the second-named tube and lying opposite the first-named hand-wheel, a rod projecting through the second-named tube and movable independently thereof, and means for transmitting the movements respectively of the tubes and of the rod.

5. The combination of a tube, means for mounting the same to swing on a transverse axis, a rack, a sleeve arranged to turn on the tube and also to move longitudinally thereof into and out of engagement with the rack, a hand-wheel connected with the sleeve, a tube mounted to turn in the first-named tube, a second hand-wheel connected with the second-named tube and lying opposite the first-named hand-wheel, a rod projecting through the second-named tube and movable independently thereof, means for transmitting the movements respectively of the tubes and of the rod, and a latch mounted on one of the hand-wheels and adapted removably to hold the wheels in close engagement with each other.

6. The combination of a swinging member, a turning member carried thereby, a round sleeve connected with the turning member and a rack with which the sleeve engages, said rack having teeth curved concentrically to the cross-sectional form of the sleeve, and means for transmitting the movements of the said members.

7. The combination of a swinging member,

a turning member carried thereby, a round sleeve connected with the turning member and a rack with which the sleeve engages, said rack having teeth curved concentrically to the cross-sectional form of the sleeve, means for transmitting the movements of the said members, 30 a rod carried within the second-named member, and means for transmitting the movement of the rod.

8. The combination of a tube mounted to swing, a second tube carried movably therein, a member forming a dog carried by the first-named tube, a rack with which said member coacts, a hand-wheel attached to the second-named tube, a rod extending through the 40 second-named tube, and means for transmitting the movements of the two tubes and of said rod.

In witness whereof I have hereunto set my hand in presence of two witnesses.

HENRY SÉCHAUD.
